FURNACE

Ervin G. Bailey, Easton, Pa., assignor, by mesne assignments, to The Babcock & Wilcox Company, Newark, N. J., a corporation of New Jersey

Application July 10, 1934, Serial No. 734,456
Renewed February 20, 1937

16 Claims. (Cl. 122—235)

This invention relates to improvements in fluid heat exchange apparatus, and more particularly to improvements in furnaces which have combustion chamber walls cooled by fluid circulating in tubes in the walls.

In the construction and operation of furnaces having fluid cooled walls it is advantageous to employ rows of fluid conducting tubes as the structural strength members of the combustion chamber wall, and such tubes are used in this way in the practice of the present invention. Excessive cooling of the combustion gases is prevented by the maintenance of refractory material upon the furnace sides of the tubes. When the furnace face of this refractory material is heated to high temperatures it promotes adequate combustion within the furnace, and simultaneously limits the temperature rise of the metal surfaces over the temperature of the contained cooling fluid.

To promote adequate heat transfer from the refractory facing to the fluid conveyed by the tubes of the furnace wall, the furnace sides of the tubes are provided with welded, metallic extensions suitably spaced and of adequate heat conducting cross-section. These extensions bond the refractory lining and have the function of mechanically as well as thermally maintaining the refractory facing upon the fluid cooled metallic surfaces.

The furnace included in the present invention is of such a character that it has different parts of its walls formed by rows of spaced tubes. The corresponding ends of the rows of tubes are connected by chambers such as headers or drums. One set of tubes may be connected to a drum whereas another set of tubes forming another part of the furnace wall may be connected to a header and the header may be adjacent the drum. In many instances, it is not feasible to locate headers or drums in positions spaced materially from or outside of the furnace wall, and in fact, in many cases in the construction of boilers, it is of particular advantage to locate the drums or headers in such positions that the furnace wall tubes extending therefrom are exposed to heat from the furnace gases over their entire lengths. A bottom supported water tube wall is an important example. This invention provides a combination which permits the drums or headers to be located in the last mentioned position without the sacrifice of operating advantages.

Another object of the present invention is to ameliorate conditions which tend to produce tube seat leakage by providing the region of the junc-

tions of the tubes with the headers or drums with a heat resistant permanent facing which may be economically applied and maintained, and which may at the same time serve to raise furnace temperatures above values that would exist without such facing.

It is specifically within the purview of the invention that the steam generating tubes of a boiler, and an associated boiler drum (or equivalent fluid chamber) may be so modified that they act as fluid cooled walls and have the advantageous operating characteristics of the latter, and the invention may be applied to existing boilers to improve them as well as be embodied in new ones.

Different embodiments of the invention are shown in the accompanying drawings, in which:

Fig. 1 is a detail view showing a portion of a water tube boiler having a water cooled furnace wall header and an adjacent boiler drum.

Fig. 2 is a detail section showing tubular fluid heating members to which welded metallic studs and a refractory facing are applied. This view is on the line 2—2 of Fig. 1.

Fig. 3 is a transverse section through a portion of a furnace wall including tubes with diametrically opposite longitudinal flanges or fins to which the welded studs and refractory facing are applied.

Fig. 4 is a vertical section of a part of a furnace construction having a water tube hopper bottom inclined on two sides, the other two sides having straight water tubes ending in bottom headers.

Fig. 5 is a vertical section on the line 5—5 of Fig. 4.

Fig. 6 is a section of a part of the construction indicated in Fig. 5, made on a much larger scale.

Fig. 7 is a transverse section of the boiler shown in Fig. 1 placed over a furnace.

Referring to Figure 1 of the drawings the tubes 16 are boiler tubes which are preferably arranged so that they are exposed to the fire of an adjacent furnace. These tubes are expanded in a drum 15 at their lower ends, one side of the drum 45 facing the furnace. The sides of the tubes toward the fire have the spaced metallic studs 5 welded thereto. The refractory material 6 is indicated as embedding the studs and extending over the tubes so as to constitute a wall interposed between the furnace and the tubes so that the furnace is made hotter than it otherwise would be. Similar studs 5' are spaced over the furnace side of the drum 15 and welded thereto, and the refractory material 6 extends past the 55

tubes to also cover the furnace side of the drum. The facing on the drum also contributes to the raising of the furnace temperature, while the facing on both tubes and drum promotes equalization of metal temperatures.

Spaced from the drum 15 is the header 12 connected to tubes 18 which extend along a wall of the furnace. As shown, the header 12 is a water wall header preferably in connection 10 with the boiler circulation. In the parent application 39,010, this header and its associated structures are described in the following language:

"Figs. 7 and 8 (Figs. 1, 2 and 3 of the present 15 case) illustrate certain portions of the boiler circulating system in a common type of boiler construction which are exposed more directly than the rest to the action of the most intense flame and heat from the fire, and which in consequence 20 frequently burn out and have to be replaced while the other less exposed portions of the boiler still remain in good condition.

As an example of such portions of the boiler a 25 transverse manifold is indicated at 12, a transverse water container or mud drum at 15 and a bank of circulating tubes 16, which extend upward from the drum, 15, to the steam drum (not shown)."

Short welded studs 22 extend from the header 30 12 toward the furnace interior and longer welded studs 28 extend toward the drum 15. These studs are embraced by refractory material which preferably constitutes a continuation of the layer extending over the tubes 16 and the interposed wall 35 of the drum. The combination covering serves the double purpose of closing the space between header and drum and equalizing metal temperatures.

Figure 5 of the drawings indicates a furnace 40 wall in which a lower refractory wall section without water tubes includes refractory blocks on its cooler side. As shown, the block supports are metallic, and the top section has a hooked element 38 resting upon the angle 32 carried by the main support of the water tube wall above. The upper end of the refractory wall section is located adjacent the lower water wall header 34 into which the wall tubes 36 are expanded. Tube 45 space closure wall blocks 38 and ledge blocks 46 are preferably secured to the wall tubes to complete this section of the water tube wall. Whereas this refractory is but a part of the illustrated combination it will be understood that the illustrated refractory wall is representative, and that 50 a stud tube wall might be substituted.

Contacting with the upper and lower wall sections and closing the joint between them is a body of refractory material 42 located in front of the header 34 and held in place thereon by the 55 studs 44 welded to the header.

The wall structure indicated in Figs. 5 and 6 is shown in Fig. 4 to be embodied in the two vertical side walls of a hopper bottom furnace having the other two of its sides delineated by the 60 downwardly converging water tubes 48 which are bent outwardly at their lower ends and connected to the headers 52. Tube space closure wall blocks 54 are shown positioned along the furnace sides of the tubes 48. On their opposite sides are 65 layers of insulation material 56.

The furnace wall indicated in Fig. 3 includes the spaced wall tubes 2 provided with the longitudinal fins 3 which are positioned at diametrically opposite parts of the tubes and are aligned 70 in planes parallel to the face of the furnace wall.

Welded projections 58 in the form of ribs or studs extend into a refractory facing preventing the ends of fins from being burned as well as completing the space closure between tubes.

When the tubes with their welded metal projections are not covered by refractory or have only a comparatively thin covering of refractory material, slag from ash in the fuel will be fused when the furnace is operated at a high rate, and will accumulate on the projections which are prevented from excessive burning by the resultant cooling effect of the fluid within the tubes. Thus the ash itself may form a suitable coating upon the tubes to produce the temperature conditions required in the furnace and in the metal parts of the walls. The rapidity and effectiveness of this action will vary somewhat according to the nature of the fuel being used, size of furnace, and ratio of refractory to tube cooled area, so that it is not in all cases necessary to apply a coating of refractory material to the welded projections on tubes, headers or drums, before the furnace is put into operation, but a preliminary covering of suitable refractory material on the metal more quickly brings the furnace and boiler to its normal operating condition.

The metal projections which hold the refractory furnace side facing of the tubes, header or drum metal must have adequate thermal conductivity to avoid excessive differences between their tips and their bases, and to protect the refractory from overheating as well as to mechanically hold it, and I have found electric welding to be a satisfactory way of thermally bonding the projections to the fluid cooled tube header or drum.

While the invention has been described with reference to certain particular embodiments it is to be understood that it is not limited thereto, but that it is of a scope commensurate with the scope of the subjoined claims.

This application is a continuation-in-part of my application Serial Number 39,010, filed June 23, 1925.

What is claimed is:

1. In fluid heat exchange apparatus, a furnace, a fluid chamber in the form of a header or drum extending transversely of a wall of the furnace in proximity thereto and exposed to heat from the furnace, tubes communicating with the chamber and extending along a side of the furnace, metallic studs distributed over the sides of the tubes and the chamber facing the interior of the furnace and welded thereto and refractory material extending over said sides and around the studs.

2. In fluid heat exchange apparatus, a furnace, a fluid chamber extending transversely of a wall of the furnace and exposed to heat from the furnace, tubes communicating with the chamber and delineating a side of the furnace, metallic members distributed over the sides of the tubes and the chamber facing the interior of the furnace and welded thereto, and refractory material extending over said sides and around the studs, said refractory material covering said sides as a layer and extending over the junctions of the tubes with the chambers.

3. A boiler furnace, a row of spaced fluid cooled tubes along a side of the furnace, a water chamber extending transversely of the row and connected to the tubes, the chamber being exposed to heat from the furnace, metallic studs welded to the tubes over their furnace faces and to the chamber wall presented toward the furnace, and

rigid refractory material applied in non-rigid condition over the faces of the header and the tubes having the metal members thereon, said refractory material forming a shield covering the junctions of the tubes and the chamber wall.

4. In a furnace, means for burning fuel in the furnace, spaced fluid conducting tubes, a drum forming a connection for the tubes, metallic studs distributed over the sides of the tubes and the drum facing burning fuel in the furnace, a water wall header adjacent the drum, studs welded to the header, a refractory layer positioned between the projections and extending over the furnace sides of the drum and header to form a gas boundary wall connecting them.

5. In fluid heat exchange apparatus having parts exposed to the heat of a furnace and comprising, in combination, a row of tubes conducting a fluid past a heating zone wherein the fluid receives heat transmitted from the burning fuel through the tube walls, a fluid chamber to which the tubes are connected, a wall of the chamber exposed to the same heating zone as the tubes, and an outer composite structure extending over the tubes and said chamber wall to act as a shield interposed between the chamber and the burning fuel; said outer structure including metallic studs welded to the tubes and the chamber wall, and a rigid refractory layer positioned over the furnace faces of the tubes and the chamber while in a non-rigid condition, the projections acting to control the heat exchange and prevent excessive erosion of the refractory by cooling the refractory.

6. Fluid heat exchange apparatus acting as a part of a furnace and comprising, in combination, an inner structure consisting of a row of aligned tubes and a connected drum conducting a fluid past a heating zone wherein the fluid receives heat transmitted from burning fuel through the tube and drum walls; and an outer composite structure including metallic projections welded to the tubes and the drum, and a slag layer deposited by the products of combustion moving from the burning fuel and extending across the tubes and the drum and embedding the projections to form a shield between the drum and the tubes and the burning fuel, the projections acting as supports or anchors for holding the deposited slag layer in operative position, said row of tubes absorbing a preponderance of heat on one side of the row.

7. In a tubular heat exchanger exposed to heat from a furnace to transmit to a contained fluid the heat received radiantly from fuel burning in the furnace; said tubular heat exchanger having a metallic inner structure consisting of the walls of tubes and a fluid chamber connected to the tubes, said walls being in contact with the contained fluid; and a composite outer structure exposed to radiant heat from the burning fuel; said outer structure comprising metallic extensions extending outwardly from and welded to the tubes and a wall of the chamber, and refractory materials contacting with the inner part and located between the extensions, said refractory materials extending over said walls and being of greater thermal resistance than the material of the remaining structure, thereby preventing overheating of the exchanger metal and contributing to higher furnace temperatures.

8. A furnace wall having a horizontally arranged header, metallic refractory retaining members projecting from and welded to the furnace side of said header, and refractory at the

furnace side of said header covering and held on said header by said retaining members.

9. In a tubular heat exchanger adapted as a part of a steam boiler and its furnace to transmit to a contained fluid the heat received radiantly from fuel burning in the furnace; said tubular heat exchanger having a row of spaced tubes extending across the path of furnace gases and constituting a metallic inner structure in contact with the contained fluid and including metallic means forming a pressure chamber in the form of a header or drum communicating with the tubes; and a composite outer structure exposed to radiant heat from the burning fuel; said outer structure comprising metallic projections extending outwardly from the tubes and the drum or header of the inner structure and rigidly connected therewith, with the projections on at least some of the tubes independent of the projections on others of the tubes, and refractory material contacting with the inner structure and located between the projections; said refractory material being of greater thermal resistance than the material of the remaining structure to thereby prevent overheating of the exchanger metal and contribute to higher furnace temperatures.

10. In a tubular heat exchanger adapted as a part of a steam boiler and its furnace to transmit to a contained fluid the heat received radiantly from fuel burning in the furnace; said tubular heat exchanger having an inner part consisting of a row of steam generating tubes and means forming a lower water chamber communicating with said tubes; and a composite outer structure exposed to radiant heat from the burning fuel; said outer structure comprising metallic projections extending outwardly from the tubes and water chamber of the inner part toward the burning fuel and rigidly connected with the inner part, with the projections on at least some of the tubes independent of the projections on others of the tubes, and refractory material contacting with the inner part and located between the projections; said refractory material being of greater thermal resistance than the material of the remaining structure to thereby prevent overheating of the exchanger metal and contribute to higher furnace temperatures.

11. In a tubular heat exchanger adapted as a part of a steam boiler and its furnace to transmit to a contained fluid the heat received radiantly from fuel burning in the furnace; said tubular heat exchanger having a row of spaced tubes constituting a metallic inner part in contact with the contained fluid; and a composite outer structure exposed on corresponding sides of the tubes directly to radiant heat from the burning fuel; said outer structure comprising metallic projections extending outwardly from the inner part toward the burning fuel and rigidly connected with the inner part, with the projections on at least some of the tubes independent of the projections on others of the tubes, and refractory material contacting with the inner part and located between the projections; said refractory material being of greater thermal resistance than the material of the remaining structure to thereby prevent overheating of the exchanger metal and contribute to higher furnace temperatures, said tubes being bare and directly exposed to furnace gases on their sides opposite said outer structure; the tubes with their refractory facings being definitely spaced apart to allow furnace gases to pass between them.

12. In a tubular heat exchanger adapted as a

- part of a steam boiler and its furnace to transmit to a contained fluid the heat received radiantly from fuel burning in the furnace; said tubular heat exchanger having a row of tubes extending across the path of the furnace gases constituting a metallic inner structure in contact with the contained fluid; means for connecting said tubes into a fluid circulation; means for burning a slag forming fuel in the furnace so that the furnace gases pass between said tubes and deposit thereon combustion solids carried in suspension before the gases contact with other rearwardly disposed fluid heat exchange surface; and a composite outer structure exposed to radiant heat from the burning fuel; said outer structure comprising metallic projections extending outwardly from the inner structure and rigidly connected therewith, with the projections on at least some of the tubes independent of the projections on others of the tubes, and refractory material contacting with the inner structure and located between the projections, said refractory material being of greater thermal resistance than the material of the remaining structure to thereby prevent overheating of the exchanger metal and contribute to higher furnace temperatures; the tubes and their refractory facings being definitely spaced apart to allow furnace gases to pass between them.
13. In a tubular heat exchanger adapted as a part of a steam boiler and its furnace to transmit to a contained fluid the heat received radiantly from fuel burning in the furnace; means forming a lower water chamber; means forming an upper steam and water chamber, means for burning a slag forming fuel in the furnace so that the furnace gases will carry solids in suspension; spaced tubes communicating with said chambers and extending across the path of furnace gases to allow gases to pass therebetween and constituting a metallic inner structure in contact with the contained fluid; and a composite outer structure exposed to radiant heat from the burning fuel and acting to receive the solids carried in suspension by the furnace gases before they contact with rearwardly disposed fluid heat exchange surfaces; said outer structure comprising metallic projections extending outwardly from the inner structure and rigidly connected therewith, with projections on at least some of the tubes independent of the projections on others of the tubes, and refractory material contacting with the inner structure and located between the projections, said refractory material being of greater thermal resistance than the material of the remaining structure to thereby prevent overheating of the exchanger metal and contribute to higher furnace temperatures; the tubes and their refractory facings being definitely spaced apart to allow furnace gases to pass between them.
14. In a tubular heat exchanger adapted to transmit to a contained fluid the heat received from furnace gases and having an effective length positioned entirely within a furnace gas space; said tubular heat exchanger including spaced units each having a metallic inner part to contact with a contained fluid; and a composite outer

structure adapted to be exposed directly to furnace gases which pass on substantially all sides thereof; said outer structure comprising metallic projections extending outwardly from the inner part and rigidly connected therewith, and refractory material contacting with the inner part and located between the projections; said refractory material being of greater thermal resistance than the material of the remaining structure to thereby prevent overheating of the inner part, and a part of the metal of the unit being bare in a zone extending longitudinally of the unit and defined at opposite sides by the refractory material.

15. In tubular fluid heat exchange devices adapted as parts of a steam boiler and its furnace to transmit to a contained fluid the heat received radiantly from fuel burning in the furnace; said devices including a bank of spaced tubes the front tubes of which constitute metallic inner parts in contact with the contained fluid, the bank of tubes being contacted and enveloped by furnace gases passing through and across the bank; and composite outer structures exposed on the front sides of the front tubes of said bank directly to radiant heat from the burning fuel; said outer structures including metallic projections extending outwardly from the inner parts toward the burning fuel and rigidly connected with the inner parts with the projections on the individual tubes independent of the projections on other tubes, and refractory material contacting the inner parts and located between the projections; said refractory material being of greater thermal resistance than the material of the remaining structure to thereby increase the capacity and operative life of the boiler, prevent overheating of exchanger metal, and contribute to higher furnace temperatures; the tubes and their refractory facings being definitely spaced apart to allow furnace gases to pass between them.

16. In tubular fluid heat exchange apparatus adapted to transmit to a contained fluid the heat received from furnace gases; said apparatus including spaced tubes enveloped by the furnace gases and constituting metallic inner parts in contact with the contained fluid; and composite outer structures directly exposed on corresponding sides of the tubes to the furnace gases; said outer structures including metallic projections extending outwardly from the inner parts toward the furnace gases and rigidly connected to inner parts, with the projections on different tubes independent of each other, and refractory material contacting with the inner parts and located between the projections; said refractory material being of greater thermal resistance than the material of the remaining structure to thereby prevent overheating of the exchanger metal and contribute to higher furnace temperatures, said structures presenting bare metal on the sides of the tubes opposite the outer structures, the tubes and their refractory facings being definitely spaced apart to allow furnace gases to pass between them.

ERVIN G. BAILEY.
